UNITED STATES PATENT OFFICE.

JOHN SHERMAN McCHESNEY, OF CHICAGO, ILLINOIS.

WIRE-TYING.

1,360,237.

Specification of Letters Patent. Patented Nov. 23, 1920.

Application filed January 26, 1917. Serial No. 144,604.

To all whom it may concern:

Be it known that I, JOHN SHERMAN McCHESNEY, citizen of the United States, residing at Chicago, Illinois, have invented 5 certain new and useful Improvements in Wire-Tying; and I do hereby declare the following to be a full, clear, and exact description of the invention, such as will enable others skilled in the art to which it applies 10 pertains to make and use the same.

My invention relates to the wire-tying of articles and the formation of endless wire loops, its general objects including the producing of an endless wire loop quickly and 15 effectively and without any waste of wire. In one aspect, my invention relates to the production of wire loops or bands from a supply of the wire or the like without overlapping, intertwisting or otherwise doubling 20 up on the amount of wire needed for any portion of the loop, and without producing objectionable projections on the loop. In another aspect, my invention relates to the production of wire loops embracing a given 25 object or objects with a predetermined tension, and to the obtaining of this given tension without waste of wire even when different portions of the wire stock stretch irregularly and even if the several objects 30 compress irregularly under the embrace of the wire loops. In still another aspect, my invention relates to the economical and effective use of electric welding apparatus for adjoining the ends of wire loops, and more 35 particularly for using such apparatus upon loops formed around the object or objects to be embraced by the same.

Heretofore, boxes or other objects have commonly been banded with wire by wrapping a previously cut piece of wire around the object and then intertwisting the ends of the wire. This method not only leaves an unsightly and objectionable projecting wire twist, but usually wastes wire (since 40 neither the stretching of each particular piece of wire nor the compression of the object embraced by the same can be predicted), often damages the wire by an undue strain upon the same during the twisting, and 45 lacks uniformity in the tightness with which the various bands encircle the objects. In my copending applications, filed Nov. 13, 1916 and January 6, 1917 as Serial Nos. 130941 and 140883 respectively, I have disclosed means for overcoming a part of these 50 objections by controlling the tension on the

wire so as to secure a uniformity of embracing pressure on the encircled object, thereby compensating for irregularities in the stretching of the wire. However, the 60 method thus disclosed still requires a considerable overlapping of wire for the production of the twist or twists, and also requires the wasting of a small amount of wire which is cut off just before the twisting is 65 completed. My present application aims to overcome this waste of wire altogether by cutting the wire from the supply reel only after it has been tensioned about the object to determine the exact amount of wire 70 needed; and also aims to substitute welding for the intertwisting operation, thereby saving the amount of wire required for the overlapping and intertwisting involved by the method of my said copending applications. Other and more detailed objects of 75 my invention will appear from the following specification and from the accompanying drawings, in which drawings:—

Figure 1 is a plan view of an apparatus 80 suitable for carrying out the method of my invention.

Figs. 2 and 3 are transverse vertical sections, taken respectively along the lines 2—2 and 3—3 of Fig. 1.

Fig. 4 is a bottom view of a package tied by the method of my invention, showing in dotted lines the initial position of the supply end of the wire.

Fig. 5 is a diagrammatic view showing the 90 method of welding the wire loop ends after the wire has been cut to length.

Fig. 6 is an enlarged view of the finished juncture of the wire loop ends.

Fig. 7 is a fragmentary plan view of the 95 left hand portion of Fig. 1, showing the loop portion of the wire cut from the supply portion and moved into alignment with the other end of the loop.

Figs. 8, 9 and 10 are diagrammatic views 100 showing three successive positions of the wire comprising the loop.

Generally speaking, I accomplish the purpose of my invention by these steps:

(1) By gripping the free end of a coil 105 or reel of wire and looping the adjacent wire around the given object.

(2) By gripping the loop at some distance from the other end of the needed amount of wire and tightening the loop around the 110 object to a predetermined tension.

(3) By gripping the loop close to the last

named end and severing the requisite length of wire for the loop from the coil or reel.

(4) By bringing the loop ends into contact and preferably into alignment longitudinally of the wire.

(5) By uniting the loop ends to each other, preferably by electrically welding the same.

Illustrative of my method. Fig. 1 shows a hand-operated apparatus for use with the same, including a table 1 carrying a transverse slide 2, which slide is connected through a link 3 with a lever 4. The table 1 also carries another slide 5 arranged to be moved longitudinally of the table by cams 6 operated by a lever 7, and a third slide 8 carrying opposed spring-actuated jaws 9 and adapted to be reciprocated longitudinally of the table by a lever 10. In starting the wire banding of an object adapted to be suitably supported above the aforesaid parts by pillars 11, I first grip the free end 12 of the supply of wire in the jaws 13 (which jaws may be relatively moved by means of a cam 14), the end being placed with its extreme tip abutting against a stop 15 carried by the transverse slide 2. I then form the wire into an approximately vertical loop as shown in Fig. 8, slipping the supply portion of the wire between jaws 16 (also carried by the slide 2), spring-pressed opposed jaws 17 carried by the table, and the said jaws 9 on the reciprocable slide 8. Next I insert the desired object (shown in dotted lines in Fig. 9) within the loop and oscillate the lever 10 about its pivot, thereby reciprocating the thrust-bar 18 which is connected to the wire-tensioning slide 8 through a compression spring 19. Each movement of the lever 10 in the direction of the arrow 40 tightens the loop by drawing the supply portion 20 of the wire toward the right, a retracting of the wire during the return movement of the lever 10 being prevented by the spring jaws 17. Thus the loop is gradually tensioned by progressive steps about the said object until the tension of the wire effectively equals the resistance of the spring 19, after which any further movement of the lever 10 in the direction of the arrow will only compress this spring without moving the slide 8.

This leaves the wire looped about the object as shown in Fig. 9, with the supply portion of the wire disposed out of alignment with the free end of the wire. I then move the lever 4 toward the left, thereby moving the slide 2 and (through the intermediary of the spring 21) forcing the jaws 16 (which at first were separated to allow the wire to be freely inserted between them) to grip the wire, and then severing the wire of the loop approximately in transverse alignment with the original tip 12 of the wire by a cutter 22 on the slide 2. While the wire is being cut, the jaws 16 (being also moved with the

slide 2) move the wire portion 23 transversely, thereby bringing the freshly cut end of the wire into alignment with the initial tip of the wire, any further movement of the jaws 16 being prevented by their engagement with stops 24 on the table. This leaves the wire loop severed from the supply of wire, with all portions of the loop disposed substantially in a common plane and with the two ends of the loop disposed close to each other and in alignment with each other as shown in Figs. 5 and 7. I then move a companion handle 25 which first moves the jaws 13 through the slide 5 and the cams 6, so as to abut the tips of the wire 80 end firmly against each other, then complete the welding circuit through the contacts 26 and 27 to the respective clamps 13 and 16 as shown in Fig. 5 (the circuit connections and insulating elements having been omitted from the drawings to prevent confusion) and thereafter move the clamp 13 and the original tip of the wire toward the other tip during the welding operation, the duration of which operation is automatically controlled by a timing circuit-breaker 30 (Fig. 5). This final movement of the original wire tip presses the wire ends tightly together while softened by the heating and compensates for the extra stock required to form the usual bur, as shown in Fig. 6. As soon as the weld is completed, the wire-tripping jaws are released by means of the cam-handles 28 and 29, thereby permitting the banded object to be removed from the appliance. Then the contact between the elements 26 and 27 is interrupted by moving the handle 25 to the right (in doing which the cams 6 engage hooks 31 on the slide 5 so as to return the latter to its starting position), the circuit-breaker 30 is reset, and the end of supply wire is snapped out of the grips 17 and 9, thereby completing the cycle of steps.

It will be obvious from the above that the wire is first looped about the object with the proposed terminals of the loop out of alignment with each other, as in Fig. 8, and that the tensioning of the wire prior to cutting the latter brings the upper loop portion (horizontal in Fig. 9) and the two vertical portions into a common plane with the tip end of the wire which is gripped by the clamp 13, leaving the supply portion of the wire out of alignment with this plane. Then the movement of the handle 4 not only cuts the wire to the desired length, but also swings the freshly cut end of the loop into the said plane. As this cutting is done at a point fixed with respect to the stop 15 which definitely locates the original free end of the wire, and is done after the loop has been tightened to a predetermined tension, my method automatically compensates for variations in the ductility of the wire portions

used for different loops, and in differences of size or compressibility of the banded object. So also, since the approaching of the jaws 16 and 13 is practically a constant when using current at a given voltage and for a fixed time interval on wire of a given size, the final added tensioning and the resulting tightness of the banding will likewise be uniform, so that I am able to secure any desired firmness of banding without overstraining the wire and with no waste of wire.

However, while I have pictured and described certain apparatus for employing my method, I do not wish to be limited to the same, nor to the particular details as here disclosed, it being obvious that the same might be varied in many ways without departing from the spirit of my invention. For example, the diagram of Fig. 5 shows a pair of intermeshed gear sections for operatively connecting the lever 25 with the gripping jaws 13, instead of the link and cam arrangement of Fig. 1.

25 I claim—

1. The method of banding an object with wire, consisting in looping the wire, tensioning the loop about an object to a predetermined degree, severing excess wire from the loop, and then increasing the tension of the loop and securing the ends thereof.

2. The method of banding an object with wire or the like, which consists in looping the wire around the object, tensioning the loop, to cause the same to grip the object, cutting the wire to the required length while under tension, increasing the tension of the loop and concurrently uniting the ends of the loop by a butt weld and without shifting the plane of the loop.

3. In a wire banding machine, means for holding one end of a loop-forming wire, yieldable means for predeterminedly tensioning the loop, and means for increasing the tension of the loop beyond the predetermined tension and joining the ends of the loop.

4. In the banding of an object with wire along a predetermined plane transverse of the object, the steps of looping the wire around the object with all except the supply portion of the wire in the said plane, tensioning the wire while thus disposed, severing the loop wire while under tension from the supply, swinging the freshly severed end of the loop into the said plane, and uniting the ends of the wire loop.

5. In the banding of an object with a wire, the steps of looping the wire around the object with all except the supply portion of the wire in a common plane with the free end of the wire, tensioning the wire, while thus disposed, severing the loop wire from the supply, while maintaining the said tension, swinging the freshly severed end of

the loop into the said plane, and thereafter uniting the ends of the wire loop while increasing the tension on the loop.

6. The method of making a wire loop, which includes the disposing of the wire for the loop with all except a relatively short portion thereof in a common plane, severing the wire for the loop from the supply, swinging said wire portion into said plane without shifting the plane, and thereafter uniting the ends of the wire loop.

7. In the making of a wire loop, the steps of gripping wire portions disposed near the ends of the requisite length of wire while the said portions are out of alinement and while the wire is under tension, relatively moving the wire-gripping means to bring the said wire portions into alinement while maintaining the tension thereon, and thereafter butt-welding the ends of the wire to each other while increasing the tension on the wire.

8. In an appliance for banding an object with a loop of wire, a support for the object, means for holding wire in loop formation encircling the object and with all except the supply end of the loop disposed in a predetermined plane transversely of the object, means for tensioning the loop about the object without shifting the plane of the said major loop portions, means for severing the loop from the supply of wire while maintaining the said tension and without shifting the plane of the said major loop portions, means for swinging the supply end of the loop into the said plane, and means for thereafter uniting the loop ends while maintaining the tension on the loop.

9. In a wire banding machine, means for holding one end of a loop-forming wire, other means for holding the opposite end of the wire in opposing relation to the first end, movable means supporting one of the aforesaid means whereby the ends of the loop may be brought together, means for joining the ends of the loop, and means for actuating the movable means and simultaneously effecting operation of said joining means.

10. In a wire banding machine, means for holding one end of a loop-forming wire, a support for said means movable lengthwise of the wire, means for holding the opposite end of the wire while the first end is brought into contact therewith, means for moving the support to bring the ends of the wire together, and electric welding means for joining the ends of the wire including a circuit closing switch closable by and during operation of said support-moving means.

11. In a wire loop forming machine, a slide, means thereon for securing one end of a loop-forming wire, a second slide movable transversely of the path of the first slide, means on the second slide for holding the opposite end of the wire, means for sev-

ering the second end of the wire from a supply by and during movement of the second slide, and means for moving the slides.

12. In the wire-banding of a rectangularly sectioned box, disposing wire around the box in loop formation with the wire adjacent to three sides of the box in the same plane with the free end portion of the wire and with the latter portion extending partly across the fourth side of the box and with the supply portion of the wire extending across the said fourth side at an angle to the said plane; tensioning the loop about the box while thus disposed, severing the loop from the supply while maintaining the said tension, swinging the said angularly disposed part of the loop into the said plane, and then simultaneously increasing the tensioning of the loop and securing the tips of the loop to each other.

13. In a wire loop forming machine, a slide, means thereon for securing one end of a loop-forming wire, a second slide movable transversely of the path of the first slide, means on the second slide for holding

the opposite end of the wire, means for severing the second end of the wire from a supply by and during movement of the second slide, and means for moving the slides, and means operable by and during the operation of the first slide to effect joining of the ends of the wire loop.

1. In the banding of a package with wire, encircling the package loosely with a loop of wire, gripping the free end of the wire, disposing all except the supply end of the wire in a given plane transverse of the package and disposing the said supply end at a slight angle to the said plane, tensioning the loop about the package while thus disposed, gripping the supply end of the loop near its other proposed end, severing the loop wire from the supply without relaxing the said tension, swinging the said gripped supply end into the said plane, and welding the loop ends to each other while maintaining the tension on the loop.

Signed at Chicago, January 24th, 1917.

JOHN SHERMAN McCHESNEY.
